UNITED STATES PATENT OFFICE

2,098,032

CONTACT MECHANISM

John A. Favre, Rutledge, Pa., assignor to General
Electric Company, a corporation of New York

Application March 23, 1937, Serial No. 132,513

16 Claims. (CL 200—153)

My invention relates to improvements in contact mechanisms, and more particularly to contact mechanisms for electroresponsive devices, such as relays and the like, and an object of my invention is to provide an improved contact mechanism whereby to eliminate rebound; that is, separation of the contacts one or more times after their first engagement. This and other objects of my invention will appear in more detail hereinafter.

10 In electroresponsive devices, such as quick-acting sensitive relays, which respond to fault conditions for the protection of electric circuits, the relatively movable co-operating contacts of the relay must engage quickly and stay engaged long enough to fulfill the protective relay function. But since at least one of the contacts must be quickly actuated, and when once moving it tends so to continue, considerable kinetic energy must be suitably disposed of when the contacts engage. Otherwise, the sudden stopping of the movable contacts will result in rebound or contact bouncing; that is, a separation of the contacts followed by successive reclosures and openings. Obviously, such action of the contacts is erratic, 25 insofar as the purpose for which the relay is installed is concerned, because the desired protection is endangered by this uncertainty of contact closure. Such rebounding or bouncing action is further troublesome in relays involving so-called "memory action", wherein, although initially there may be ample force to effect contact closure, such force may so rapidly diminish as to be sufficient merely to maintain contact closure if the bouncing is not present.

30 In accordance with my invention, I provide means whereby the kinetic energy of the moving contact mass is substantially instantaneously transferred or imparted to other movable means which are arranged to dissipate the energy they receive without such reaction on the closing contacts as to produce separation thereof after engagement. Further in accordance with my invention, I may provide means whereby in the case of excessive forces acting on the movable contact structure, such forces may be allowed, in part at least, to expand themselves without having the contact structure act as an abutment against which these forces are solely exerted. While my invention is particularly adapted for use 40 in electroresponsive devices such as relays, its application obviously is not limited to devices wherein the contact mechanism is actuated only by electromagnetic means. In other words, my invention is generally applicable to contact mechanisms regardless of the character of the actuating

means, if the necessity for eliminating contact bouncing is present.

This application is a continuation in part of my copending application Serial No. 50,673, filed November 20, 1935, for contact mechanism, the subject matter in said prior application being incorporated in this application together with certain additional subject matter.

My invention will be better understood from the following description when considered in connection with the accompanying sheet of drawings, and its scope will be pointed out in the appended claims.

In the accompanying drawing, Fig. 1 is a plan view of an embodiment of my invention; Fig. 2 is a plan view of a modification of the embodiment of my invention shown in Fig. 1; Fig. 3 is a front elevation, partly in section, of the embodiment of my invention shown in Fig. 2; Fig. 4 is a partial side elevation, partly in section, looking from the right of Figs. 2 and 3; Fig. 5 is a vertical partly sectional elevation of another embodiment of my invention; Fig. 6 is an exploded perspective view of the embodiment of my invention shown in Fig. 5; and Fig. 7 is a vertical elevation of a mounting suitable for use with devices embodying my invention.

In the embodiment of my invention shown in Fig. 1, I have illustrated a contact mechanism including relatively movable co-operating contacts 10 and 11, of which contact 10 may be termed the movable contact and contact 11 the fixed contact. The contact 10 is illustrated as mounted on an arm or crank 12 which is movable by an operating member, such as a shaft 13. Obviously, an actuating force may be applied to turn the shaft 13 clockwise to produce contact engagement, by any suitable means, such as electromagnetic, electrostatic, pressure actuated, thermally operated, or otherwise, examples of all of which are well known to the art. The contact 11 may be mounted on an arm such as a leaf spring 14, which may be secured to an adjustably positioned base support 15, angularly adjustable as shown in Fig. 1, whereby to provide for contact 35 adjustments such as contact gap setting. In any given position, the motion of the spring 14 may be limited by a suitable stop means, such as an adjustably positioned arm 16 provided with a motion limiting aperture 17.

In order to prevent rebound of the contacts 10 and 11 on engagement thereof, I provide movable means for substantially instantaneously taking over or receiving the kinetic energy of the contacts 10 and 11 when they engage, and

then subsequently dissipating such transferred energy. As shown in Fig. 1, this means includes a rollable mass, such as a ball 18, which is normally in engagement with the side of the contact 11 opposite its contact-engaging surface.

The weight of the ball 18 is suitably proportioned to the mass of the moving assembly. In order to maintain the ball 18 in its correct position, and also to dissipate the energy imparted to the ball, it may be mounted in a tubular chamber 19, whose outward opening is less than the diameter of the ball and whose diameter is sufficiently close to the diameter of the ball to delay the motion of the ball in both directions. Thus, the energy of the ball is dissipated on the inward movement as air escapes from the back of the ball around its edge, and its outward movement is similarly delayed so that the ball does not return quickly enough to separate the contacts when it re-engages contact 11 on its return to the lower end of the tubular chamber 19. Obviously, this may be inclined at such an angle as to insure the desired return based on the dash-pot action of the ball in both its inward and outward movements.

In order to provide for contact adjustment, the tubular chamber 19 is preferably adjustably supported by any suitable means such as an arm 20 which, as shown in Fig. 1, is secured to an angularly adjustable base support 21. While I have shown the movable energy receiving body as a ball, it will be obvious that any suitable rollable mass may be employed. Also as shown, the contact mechanism is of the single throw type, but it will be obvious that the mechanism shown to the left of the movable contact 10 may be duplicated on the right for double throw action with another contact 10' on the arm 12.

Assuming the contacts 10 and 11 positioned as shown in Fig. 1 and that the contact 10 is suddenly actuated to engage the contact 11, the kinetic energy at the engagement will be imparted directly through the contact 11 to the ball 18 so that the contacts 10 and 11 may remain in engagement while the ball 18 rolls inwardly in its tubular channel against the dash-pot action of the air escaping around its edge. At the end of its travel in the tubular chamber 19, the ball will start rolling outwardly again under the dashpot action of the inflowing air so that it comes to rest at the end of the tube without jarring the contacts to an extent sufficient to cause separation thereof.

In the embodiment of my invention illustrated in Figs. 2, 3, and 4, instead of having the kinetic energy of the contacts transferred directly to the ball 18, I provide a second movable mass such as a ball 22, which is suitably cushioned in an outer compartment of the tubular chamber 19. For this purpose, I may provide, as shown in Fig. 4, a buffer pad, such as a felt washer 23, which is held in place against a shoulder or inner ring 24 of the chamber 19. Thus, normally the fixed contact 11 rests against the ball 22, which may just be touching the felt washer 23. When the contacts 10 and 11 engage, most of the energy of the impact is transferred through the ball 22 to the freely moving ball 18 but some is absorbed by the buffer 23 as it is compressed. The ball 18 may also have a cushioning buffer 25 to take up its energy so that it does not violently rebound from the closed end of the chamber 19. When the ball 18 slowly rolls down the inclined chamber, it meets the ball 22, which is being slowly returned as the

buffer 23 expands. Consequently, the meeting of the balls is so gradual as to effect no contact separation. This feature is of particular value in devices of the so-called "memory action" type, where the forces necessary to move the contacts to engagement rapidly decrease to a value just about sufficient to hold them closed after they are once closed. In order further to help in such cases, and also to limit refinements in adjustment, the portion of the contact 11 engaging the ball 22 may be shaped to provide a desired amount of friction between the ball and the contact. Thus the contact 11 may be recessed on its rear side, as shown more clearly in Fig. 4 to provide a large annular ring or seat engagement with the ball. Then while the ball 22 is rolling back to its normal position, some of its energy is consumed in friction against the seat on contact 11.

In Figs. 3 and 4, I have indicated only in elevation an electromagnetic means 26 of the induction type for actuating the shaft 13, since devices of this type are well known to the art. I have also shown a coiled lead-in 27 from the terminal post 28 to the movable contact 10. If desired this lead-in may also be of such a resilient character as to provide suitable bias for maintaining the contact 10 normally in a predetermined position.

Also in Fig. 3 and likewise in Fig. 2, I have illustrated further means for assisting in the prevention of rebound by a slip connection between the shaft 13 and the contact 10. As shown in Figs. 2 and 3, there is a slip clutch comprising a lower abutment 29 and an upper abutment 30, both secured to the shaft 13 so as to rotate therewith, resilient means, such as a spring 31, whose compression may be varied by the position of the upper abutment, which may be a nut threaded on the shaft, as shown, and relatively rotatable elements providing the slip feature. As shown, and beginning from the top and going down, these elements are: two washers 32 and 33, between which the spring 31 is confined and which are rotatable with the shaft 13, a felt washer 34, a metallic washer 35, an annular ring 36, which seats on the upper side of the arm 12 of the moving contact 10 and over the upper end of a hub member 37 to which the contact arm is pinned, a seal-in arm 38 which is also pinned to the hub 37, and a felt washer 39.

The seal-in arm 38 and the movable contact arm 12 are thus rotatable together, but the shaft 13 may rotate independently of both by reason of slip between the relatively rotatable parts such for example as the felt washer 34 and the metal washers 33 and 35. The seal-in arm 38 carries an armature 40 which engages the poles of a seal-in electromagnet 41. This may be energized on closure of the contacts 10 and 11 by including its winding in the circuit they energize, as is well known to the art.

In order to avoid difficulties due to the natural vibration period of the resilient contact arm 14, shown in Fig. 1, the contact 11 may be mounted on a rigid arm 14', as shown in Figs. 2 and 3. This arm is pivotally mounted at 42. In this case, a stop 43 may be provided to limit movement of the contact 11 toward its contact 10. In order to avoid any possibility of electrical contact between the lead-in 27 and the clutch spring 31, an insulating housing 44 in the form of a cylindrical shell may be provided around the spring.

In the embodiment of my invention illustrated in Figs. 5, 6, and 7, the chamber or barrel 19 houses a closely fitting ball 18 which normally rests against a diaphragm 45. This diaphragm is retained against the open end of the barrel by a flanged collar 46 suitably secured to the barrel. In order to absorb contact vibrations when the force actuating the movable contact is small and also to prevent contact chattering due to slight vibrations external to the relay, the fixed contact 11 may be mounted on a spiral spring 47 which is held in place by the collar 46 and spaced from the diaphragm 45 by a ring 48 so as to permit some slight movement of the contact 11 before effecting movement of the ball 18. The diaphragm 45, in addition to acting as a wall for holding the ball in the lower end of the barrel, also keeps out foreign matter such as dust and the like. This is important because of the close fit between the ball and the barrel for the desired dash-pot or energy dissipating action. In order to avoid difficulties from rust, corrosion, and the like, the ball 18 may be made of stainless steel and the barrel 19 of brass.

For simplification in mounting, the barrel 19 may be threaded as shown to screw into a nut 49 having a threaded hole so inclined as to insure the desired return movement of the ball. The nut 49 may be split and provided with a clamping screw 50 to lock the barrel in position for any desired contact adjustment. Obviously, the nut may be mounted on the relay device or equivalent in any suitable manner so as to provide the desired co-operation between the contacts 10 and 11.

Assuming the parts positioned as shown in Fig. 5, then if a weak force actuates the contact 10 to engage the contact 11, the relatively weak spiral spring 47 will substantially absorb the contact impact without causing any bouncing. However, if the force actuating the moving contact 10 is large, this contact will be caused to impinge against the diaphragm 45, thereby causing the shock to be transmitted to the ball 18. The resultant transfer of energy to the ball causes movement thereof upwardly in the barrel and the energy of such motion is dissipated by the dash-pot action of the ball movement in the barrel. When the ball has reached the end of its upper movement in the barrel, it rolls back gradually under dash-pot action and comes to rest against the diaphragm without causing a bouncing or separation of the contacts.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

1. A contact mechanism including relatively movable co-operating contacts, means for actuating one of said contacts to engage the other contact, and means for preventing rebound of said contacts on engagement thereof including a housing and a rollable member movable in said housing with a dash-pot effect for substantially instantaneously taking over the kinetic energy of said contacts on engagement thereof and subsequently dissipating said energy.

2. A contact mechanism including relatively movable co-operating contacts, means for actuating one of said contacts to engage the other contact, means for preventing rebound of said

contacts on engagement thereof including a housing and a rollable member movable in said housing with a dash-pot effect for substantially instantaneously taking over the kinetic energy of said contacts on engagement thereof and subsequently dissipating said energy, and means for allowing relative movement between said actuating means and said one of said contacts after engagement thereof.

3. A contact mechanism including relatively movable co-operating contacts, means for actuating one of said contacts to engage the other contact, and means for preventing rebound of said contacts on engagement thereof including a tubular housing and a ball within said housing closely fitting the bore thereof for substantially instantaneously taking over the kinetic energy of said contacts on engagement thereof, and subsequently dissipating said energy.

4. A contact mechanism including relatively movable co-operating contacts, means for actuating one of said contacts to engage the other contact, and means for preventing rebound of said contacts on engagement thereof including a housing and a rollable member within said housing movable therein with a dash-pot effect and mounted in the path of movement of said contacts for substantially instantaneously taking over the kinetic energy of said contacts on engagement thereof and subsequently dissipating said energy.

5. A contact mechanism including relatively movable co-operating contacts, means for actuating one of said contacts to engage the other contact, means for preventing rebound of said contacts on engagement thereof including a housing and a rollable member within said housing movable therein with a dash-pot effect and mounted in the path of movement of said contacts for substantially instantaneously taking over the kinetic energy of said contacts on engagement thereof and subsequently dissipating said energy, and a slip clutch between said actuating means and said one of said contacts.

6. A contact mechanism including relatively movable co-operating contacts, means for actuating one of said contacts to engage the other contact, means for preventing rebound of said contacts on engagement thereof including a rollable member in the path of movement of said contacts for substantially instantaneously taking over the kinetic energy of the contacts on engagement thereof, and means for retarding the rolling action of said member whereby to dissipate the energy transferred thereto.

7. A contact mechanism including relatively movable co-operating contacts, means for actuating one of said contacts to engage the other contact, means for preventing rebound of said contacts on engagement thereof including a ball in the path of movement of said contacts for substantially instantaneously taking over the kinetic energy of the contacts on engagement thereof and a restricted tubular channel housing said ball for retarding the rolling action thereof whereby to dissipate the energy transferred thereto.

8. A contact mechanism including relatively movable co-operating contacts, means for actuating one of said contacts to engage the other contact, means for preventing rebound of said contacts on engagement thereof including a first movable means having relatively limited movement for substantially instantaneously taking over the kinetic energy of said contacts on engagement thereof, means for limiting the move-

- ment of said first movable means, a second movable means having a larger movement for taking over the kinetic energy of said first movable means, and means for dissipating the energy transferred to said second movable means.
9. A contact mechanism including relatively movable co-operating contacts, means for actuating one of said contacts to engage the other contact, means for preventing rebound of said contacts on engagement thereof including a first rollable member movable in the path of movement of said contacts and having a limited movement for substantially instantaneously taking over the kinetic energy of said contacts on engagement thereof, cushioning means for limiting the movement of said first rollable member and absorbing some of the energy imparted thereto, a second rollable member in the path of movement of said first rollable member and engageable thereby to take over the remainder of the kinetic energy thereof, and means for dissipating the energy transferred to said second rollable member.
10. A contact mechanism including relatively movable co-operating contacts, means for actuating one of said contacts to engage the other contact, means for preventing rebound of said contacts on engagement thereof including a first ball in the path of movement of said contacts for substantially instantaneously taking over the kinetic energy of said contacts on engagement thereof, a cushion for limiting the movement of said ball and absorbing some of the energy imparted thereto, a second ball in the path of movement of said first ball for taking over the remainder of the kinetic energy thereof on engagement of said balls, and a restricted tubular channel for retarding the rolling action of said second ball whereby to dissipate the energy transferred to the second ball.
11. A contact mechanism including relatively movable co-operating contacts, means for actuating one of said contacts to engage the other contact, means for preventing rebound of said contacts on engagement thereof including a first ball in the path of movement of said contacts for substantially instantaneously taking over the kinetic energy of the contacts on engagement thereof, an annular seat on said other contact for engagement with said ball, a buffer ring for limiting the movement of said first ball and absorbing a part of the energy imparted thereto, a second ball in the path of movement of said first ball for taking over the remainder of the kinetic energy thereof on engagement of said balls, and a restricted tubular channel for retarding the rolling action of said second ball whereby to dissipate the energy transferred thereto.
12. A contact mechanism including relatively movable co-operating contacts, means for actuating one of said contacts to engage the other contact, means for preventing rebound of said contacts on engagement thereof including movable means for substantially instantaneously taking over the kinetic energy of said contacts on engagement thereof, means for providing frictional engagement between said movable means

and said other contact, and means for subsequently absorbing and dissipating the energy transferred to said movable means including a housing and a rollable member within said housing and a rollable member within said housing movable therein with a dash-pot effect.

5

13. A contact mechanism including relatively movable co-operating contacts, means for actuating one of said contacts to engage the other contact, and means for preventing rebound of said contacts on engagement thereof including a tubular housing, a diaphragm at one end of the housing mounted in the path of movement of said contacts to receive the impact of contact engagement, and a ball within said housing closely fitting the bore thereof and normally resting against said diaphragm to receive therefrom the kinetic energy of said contacts on engagement thereof and subsequently to dissipate said energy.

10

14. A contact mechanism including relatively movable co-operating contacts, means for actuating one of said contacts to engage the other contact, and means for preventing rebound of said contacts on engagement thereof including a tubular housing resiliently supporting one of said contacts at one end of the housing, a diaphragm at said end of the housing intermediate the end and said resiliently supported contact and adjacent said contact for receiving the impact of contact engagement, and a ball within said housing closely fitting the bore thereof and normally resting against said diaphragm to receive therefrom the kinetic energy of said contacts on engagement thereof and subsequently to dissipate said energy.

30

15. A contact mechanism including relatively movable co-operating contacts, means for actuating one of said contacts to engage the other contact, and means for preventing rebound of said contacts on engagement thereof including a housing, a diaphragm at one end of the housing mounted in the path of movement of said contacts to receive the impact of contact engagement, and a rollable member within said housing movable therein with a dash-pot effect and normally resting against said diaphragm to receive therefrom the kinetic energy of said contacts on engagement thereof and subsequently to dissipate said energy.

40

16. A contact mechanism including relatively movable co-operating contacts, means for actuating one of said contacts to engage the other contact, and means for preventing rebound of said contacts on engagement thereof including a tubular housing, a diaphragm at one end of the housing mounted in the path of movement of said contacts to receive the impact of contact engagement, means for resiliently supporting one of said contacts adjacent said diaphragm but normally spaced therefrom, and a ball within said housing closely fitting the bore thereof and normally resting against said diaphragm to receive therefrom the kinetic energy of said contacts on engagement thereof and subsequently to dissipate said energy.
